(57) **CLAIM**

We claim the ornamental design for a model vehicle skid pad, as shown and described.

DESCRIPTION

FIG. 1 is an upper, left, front perspective view of a model vehicle skid pad, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a lower plan view thereof; and,

FIG. 8 is an upper, right, rear perspective view of the model vehicle skid pad.

In the drawings, the broken lines illustrate portions of the model vehicle skid pad that form no part of the claimed design.

In the drawings, only the first embodiment of the model vehicle skid pad is shown. The second embodiment of the claimed design is a right model vehicle skid pad which is a mirror image of the left model vehicle skid pad disclosed in the first embodiment.
